(57) **CLAIM**

The ornamental design for a probe cup as shown and described.

DESCRIPTION

FIG. 1 is a top-front-left perspective view of a probe cup according to the claimed design.

FIG. 2 is a bottom-rear-left perspective view of the probe cup.

FIG. 3 is a rear view of the probe cup.

FIG. 4 is a front view of the probe cup.

FIG. 5 is a left side view of the probe cup.

FIG. 6 is a right side view of the probe cup.

FIG. 7 is top view of the probe cup.

FIG. 8 is a bottom view of the probe cup; and,

FIG. 9 is a sectional view of the probe cup taken along line 9-9 in FIG. 7.

The dash-dot sectional broken lines in FIG. 7 form no part of the claimed design. The oblique hatch shading in FIG. 9 illustrates portions of the probe cup along the plane of the sectional view indicated by the dash-dot sectional broken lines in FIG. 7.

1 Claim, 9 Drawing Sheets
